UNITED STATES PATENT OFFICE.

JAMES B. SCHUMAN, OF INDIANAPOLIS, INDIANA, ASSIGNOR TO HIMSELF AND JOSEPH K. SHARPE, JR., OF INDIANAPOLIS, INDIANA, AND THEOPHILUS KING, OF QUINCY, MASSACHUSETTS, A COPARTNERSHIP.

SHOCK-GRAPPLE.

No. 806,437.

Specification of Letters Patent.

Patented Dec. 5, 1905.

Application filed April 20, 1905. Serial No. 256,643.

To all whom it may concern:

Be it known that I, JAMES B. SCHUMAN, a citizen of the United States, residing at Indianapolis, in the county of Marion and State of Indiana, have invented certain new and useful Improvements in Shock-Grapples, of which the following is a specification.

The object of my invention is to provide a simple but effective means for tightly embracing a shock of corn or the like by means of which the shock may be lifted bodily, the arrangement being such that the grapple may be easily detached from the shock when the lifting has been completed.

15 The accompanying drawings illustrate my invention.

Figure 1 is a perspective view; Fig. 2, an edge elevation; Fig. 3, a sectional detail, and Fig. 4 a perspective detail.

20 In the drawings, 10 and 10' indicate a pair of strap members which are held together by suitable clips 11, which embrace the two members to permit a relative sliding thereon. The effective length of the two strap members 25 10 and 10' may be varied by means of a hook 12, carried by the member 10 and adapted to enter any one of a series of holes 13, formed in the member 10'. The free end of the member 10 carries a clip 14, into which 30 is detachably hooked a pulley-block 15. The free end of the member 10' is similarly provided with a clip 16, to which is attached a pulley-block 17. A cable 18 has one end secured to the block 17, and the other end 35 passes around the pulley-block 16 and from thence around the pulley-block 17.

Each of the strap members 10 and 10' carries a plurality of inwardly-projecting prongs 19, which are adapted to enter a shock 40 transversely, and thus prevent the strap members from slipping longitudinally of the shock.

In order to permit the easy withdrawal of the grapple, especially if the shock be laid down as it is deposited, I prefer to mount each of the prongs 19 upon a rock-shaft 20, which is pivoted in a suitable bracket 21, which is attached to either member 10 or 10'. The shaft 20 is provided with a central notch 50 21', in which lies the free end of a spring 22, the arrangement being such that the spring normally holds the prongs at right angles to

the strap members, but permitting said prongs to be swung downward in either direction parallel with the strap members, as 55 indicated in dotted lines in Fig. 2.

In operation the block 15 is unhooked from the clip 14 and the strap members are caused to embrace a shock, the prongs 19 entering the shock transversely. Block 15 is 60 then rehooked into the clip 14, and by pulling upon cable 18 the grapple may be tightened about the shock, and when it has become sufficiently tightened further pull upon the cable will serve to lift the shock bodily. 65 If the shock be laid down as it is deposited, the operator may nevertheless easily remove the grapple by unhooking the block 15 and pulling the grapple lengthwise from beneath the shock, the prongs 19 yielding to one of 70 the positions shown in dotted lines in Fig. 2. The length of the grapple may be readily adjusted by shifting the hook 12 from one to the other of the perforations 13.

I claim as my invention—

75

1. A shock-grapple comprising a flexible member, means for drawing the ends of said member together, and prongs mounted upon said member to project from one face thereof.

2. A shock-grapple comprising a flexible member, means for drawing the ends of said member together, and prongs yieldably mounted upon said member to normally project from one face thereof.

3. A shock-grapple consisting of a flexible member, and prongs mounted upon the inner face thereof, each of said prongs being pivotally supported upon an axis substantially parallel with the face of the flexible member.

4. A shock-grapple consisting of a flexible member, and prongs mounted upon the inner face thereof, each of said prongs being pivotally supported upon an axis substantially parallel with the face of the flexible member, and a spring for normally holding said prongs in a projected position.

In witness whereof I have hereunto set my hand and seal, at Indianapolis, Indiana, this 12th day of April, A. D. 1905.

[JAMES B. SCHUMAN. [L. S.]
